UNITED STATES PATENT OFFICE.

GEORGE MCNEILL, OF DETROIT, MICHIGAN, ASSIGNOR TO MORGAN & WRIGHT, A CORPORATION OF MICHIGAN.

BEAD-DRYING APPARATUS.

1,308,292.

Specification of Letters Patent.

Patented July 1, 1919.

Application filed August 10, 1916. Serial No. 114,149.

To all whom it may concern:

Be it known that I, GEORGE MCNEILL, a citizen of the United States, residing at Detroit, county of Wayne, in the State of Michigan, have invented certain new and useful Improvements in Bead-Drying Apparatus, of which the following is a full, clear, and exact description.

This invention relates to apparatus for drying beads used in the manufacture of tires. In building tires it is customary to employ beads which are formed of hard rubber composition and serve to stiffen the tires at the edges. Usually, the bead is tubed in the form of a ribbon of triangular cross-section and is ordinarily coated with cement on the sides to enhance adhesion with the edges of the tire during vulcanization. The cement coat must be dried to facilitate handling during building of the bead into a tire. The apparatus of the present invention is designed to efficiently dry the cemented bead in a substantially continuous operation.

Briefly, the invention comprises a revolvable magazine of reels upon which lengths of the cemented bead are wound. The reels are loaded at the front of the magazine and the reels are unwound at the back of the magazine, the beads being dried by heating coils around which the magazine rotates in carrying the reels from the loading point to the discharge point.

The invention can be readily understood from the following description taken in connection with the accompanying drawing, in which

Figure 1 is a side elevation of apparatus constructed in accordance with the invention.

Fig. 2 is a front elevation of the parts shown in Fig. 1.

Referring now to the drawing in which like characters of reference designate similar parts of the various views, 10 designates a frame upon which a cylindrical skeleton magazine 11 is revolvably supported at four points on the periphery by idlers 12. The magazine comprises flanged annular sides 13 connected at intervals by cross pieces 14, each one of the sides being equipped with an internal gear 15. Drive pinions 16 mesh with the internal gears and rotate the magazine as will be presently described. A circular series of reels 17 is mounted on the

exterior of the magazine, and during rotation of the latter on its axis, the reels with the cemented beads thereon are subjected to heat from heating coils 18 which are disposed within the magazine, the heat being confined in and about the reels by a casing 19 which houses the reels and may be open at the front F and the back B to respectively permit loading of and unwinding of the reels.

Each reel which is of the usual and well-known type, is provided with an axle 20 which is revolvably supported in suitable bearings 21 secured to brackets 22 which project radially from the magazine. The axle is provided on one end with a crank arm 23 by means of which the reel may be rotated, as will be presently described, to take on a single spiral layer of the cemented bead.

The reels are presented in succession at the front F of the apparatus, and to accomplish this, the magazine is power turned through successive step movements. For this purpose, preferably the above mentioned drive pinion 16 is connected to a stub shaft 24 which has a gear and worm connection 25-26 with a shaft 27 which is driven by a belt pulley 28. The pulley is power turned continuously and is connected to and disconnected from a shaft as desired by means of a clutch 29 which is controlled by a shift lever 30.

Upon each reel arriving at the front of the machine, it is rotated on its axis to take on the cemented bead, and for this purpose, a drive shaft 31 is positioned on the frame 10 to align with the axle 20 of each reel as it is halted at the front of the machine. The shaft is automatically connected to and disconnected from the reel axle by mechanism comprising a sprocket wheel 32 which is provided on the side with a pin 33. Upon rotation of the sprocket wheel the pin lodges in rear of the above referred to crank arm 23 and carries the latter around with it, thereby rotating the reel to take on the cemented bead. The pin passes longitudinally of and off from the crank arm 23 when the magazine is advanced to carry the filled reel away and present an empty reel to be filled.

For driving the reel actuating shaft 31, a sprocket chain 34 is trained over the sprocket wheel 35 on a shaft 36 which is continu-

ously driven, there being a clutch 37 on the shaft and operated by a pedal 38 to connect and disconnect the sprocket wheel 35 to and from the shaft. In the present embodiment 5 of the invention, I have shown two magazines and accordingly for simplicity, I have shown the shaft 36 as being common to both machines, and as being driven by a shaft 39 and a belt drive 39' from the pulley 28 10 which rotates one of the magazines.

In operation, the shift lever 30 is moved to throw in the clutch 29 and start the magazine rotating clockwise. An empty reel will be advanced to the front F of the machine 15 and when it arrives with its axle in alignment with the reel driving shaft 31, the shift lever is moved to throw off the clutch and halt the magazine. The end of the cemented bead is now secured to the reel exposed 20 through the front of the machine, and the pedal 38 is moved to throw in the clutch 37. Thereupon the pin 33 engages with the crank arm 23 and rotates the reel which draws the bead upon itself in a single spiral layer. 25 When filled, the reel is halted by operating the pedal 38 to throw off the clutch 37. The shift lever 30 is now again operated to advance the magazine a step whereby the filled reel is carried off and an empty one presented in proper position for being loaded 30 as above described. The filled reels pass around the magazine from front to rear thereby passing around the heating coils 18. Eventually the reels arrive at the back B of 35 the machine and are there unwound successively. A sufficient interval of time elapses during passage of the filled reels around the heating coils 18 and through the heated space between the coils and casing 19, to 40 thoroughly dry the cement.

Although I have described a specific em-

bodiment of my invention, it is to be understood that modifications may be resorted to within the scope of the appended claims without departing from the spirit or sacrificing any of the advantages of the invention. 45

Having thus described my invention, what I claim as new and desire to protect by Letters Patent is:

1. A bead drying apparatus comprising a revoluble magazine, revoluble reels thereon for the beads, a shaft for driving the reels, means for turning the magazine to present the reels in succession at the shaft, and means for automatically connecting each reel to and disconnecting it from the shaft including a contact device carried by the shaft and an abutment on each reel adapted to receive the said contact device. 50 55 60

2. A bead drying apparatus, comprising a revoluble magazine, revoluble reels on the magazine for the beads, heating means inside the magazine, a casing for the magazine having a receiving end and a discharge end 65 for the beads, and drive means for imparting step rotation to the magazine including a rack device, a driving pinion engaging said rack device and a rod adapted to throw the drive means into and out of operation 70 and operable from both the receiving and discharge ends of the casing.

3. A bead drying apparatus comprising a magazine, idlers supporting the magazine from the outside, an internal gear and pinion device for rotating the magazine from the inside, revoluble reels on the magazine for the beads, and means for successively 75 rotating the reels.

Signed at Detroit, Mich., this 28th day of July, 1916.

GEORGE McNEILL.
